UNITED STATES PATENT OFFICE.

GEORGE B. SPRING, OF NEWTON, MASSACHUSETTS.

REENFORCEMENT FOR POLES.

Application filed May 21, 1926. Serial No. 110,661.

This invention relates to means for reenforcing telephone poles, telegraph poles and other similar poles and particularly to reenforcing means of that type comprising one or more vertical reenforcing members which are set into the earth alongside of the pole and are clamped thereto.

Reenforcing devices of this nature are used for reenforcing a wooden pole which has become weakened by decay. A wooden telephone or telegraph pole usually shows weakness first at the surface of the earth, the pole becoming decayed at this point before there is any appreciable deterioration of the portion of the pole above the earth or the lower end which is completely embedded in the earth.

In my application Serial No. 50,319, filed August 14, 1925, I have illustrated and described a reenforcement for poles which comprises two reenforcing members set into the earth on opposite sides of the pole and clamping devices for clamping the reenforcing members to the pole, each clamping device including a perforated plate and clamping dogs which are adjustably secured to the reenforcing members and are provided with inturned ends adapted to dog through the apertures in the pole.

My present invention relates to a clamping device of this general nature and has for its object to provide an improvement in such clamping device all as will be more fully hereinafter set forth.

In the drawings wherein I have illustrated a selected embodiment of my invention, Fig. 1 is a view of a portion of a telephone pole which is equipped with my improved reenforcing means;

Fig. 2 is a section on the line 2—2, Fig. 1;

Fig. 3 is an enlarged fragmentary sectional view to better show the construction of the clamping member;

Fig. 4 is a section similar to Fig. 2 illustrating a different embodiment of the invention;

Fig. 5 is a view showing the way in which the clamping rod is assembled with the perforated plate;

Fig. 6 is a view showing the construction which is used for poles smaller than that shown in Fig. 2.

In the drawings 1 indicates a portion of a wooden pole such as is used for telephone, telegraph and other transmission purposes, said pole being set in the earth 2.

This pole is shown as weakened by decay at the surface of the earth as indicated at 3, a condition which will be found in most wooden telephone poles after they have been in use a few years. The pole is shown as being reenforced by a reenforcing member 4 which is set into the earth alongside of the pole and which overlies the pole for a distance above the surface of the earth.

The reenforcing member may be of any suitable shape or character. In Figs. 1 and 2 it is shown as in the form of an I-beam and in Fig. 4 it is shown as in the form of commercial channel iron. The reenforcing member is clamped to the pole above the earth by the novel clamping means which forms the subject matter of the present invention.

The clamping means is of the type shown in the above-mentioned application in that it includes two clamping irons or rods adjustably connected to the reenforcing member and an intermediate perforated plate to which the clamping irons are adjustably connected. In the device herein illustrated the two clamping rods are indicated at 5 and the perforated plate at 6, the latter having perforations 7 therein. Each clamping rod 5 has one end interlocked with a perforation 7 of the plate 6 and the other end adjustably secured to the reenforcing member. Where the reenforcing member is in the form of an I-beam it will be provided with an aperture 8 through which the end of the clamping rod 5 extends, the latter being screw-threaded as shown at 9, and provided with a clamping nut 10. The end of the clamping rod which interlocks with the perforated plate 6 is of special construction.

The clamping rod is bent backwardly as shown at 11 to form a hook portion adapted to enter one of the apertures 7 and in order to provide a locked engagement between the clamping member and the perforated plate the inwardly bent end of the clamping rod is formed with the toe or lip 12 which overlies and engages the inner face of the perforated plate. This forms a locked engagement between the clamping rod and the perforated plate which prevents the separation of the parts when they are in use.

In applying this reenforcement to poles the reenforcing member 4 is first driven or set into the earth alongside of the pole, as shown in Fig. 1. The clamping members

may then be applied and in so doing the two clamping rods 5 will be assembled with the perforated plate 6 in the manner shown in Fig. 5, each clamping rod being placed in 5 the full line position Fig. 5 relative to the clamping plate with the toe portion entering an aperture 7 and then being swung around into the dotted line position to connect the two parts. After the two clamp- 10 ing rods have been thus assembled with the perforated plate the clamping member is placed around the pole and the ends of the clamping rods inserted through the apertures 8 and the clamping nuts 10 applied. 15 By tightening up the clamping nuts 10 the clamp will be drawn tightly around the pole and the reenforcing member will be firmly clamped thereto. By reason of this construction there is no possibility that the 20 clamping rods 5 can become disconnected from the clamping plate 6 and, therefore, an effective clamping means is provided.

Where the reenforcing member has a channel iron construction, as shown at 13 in Fig. 25 4, I propose to provide for connecting the clamping rods thereto by attaching a plate 14 to the back of the channel iron member, the ends of the plate extending beyond the channel iron member and being bent to form 30 ears 15 to which the ends of the clamping bolts may be secured.

The reason for having a plurality of apertures in the plate 6 is to make a standard size of clamping device applicable to poles 35 of different sizes. If the pole is of smaller

dimensions than are illustrated in Fig. 2 the clamping rods 5 will be connected to the perforated plate 6 through the medium of apertures 7 which are a less distance apart than the apertures which are used in Fig. 2, 40 it being understood that the perforated plate 6 will be bent to conform to the curvature of the pole. This construction is shown in Fig. 6.

While I have illustrated herein a reenforcing means comprising a single reenforcing member 4 yet it will be understood that the invention is equally applicable to a construction embodying a plurality of reenforcing members as shown in my co-pending application Serial No. 50,319.

I claim.

A reenforcement for poles comprising a reenforcing member adapted to be set into the earth alongside of the pole and means for clamping the reenforcing member to the pole, said means comprising a perforated plate adapted to rest against the pole, a clamping rod adjustably secured at one end to the reenforcing member and having a hook portion at the other end to enter an aperture of the plate from the outer face, the terminal of the hook portion being provided with a lip to underlie the plate said lip being situated between the plate and the pole and serving to lock the clamping member to the plate.

In testimony whereof, I have signed my name to this specification.

GEORGE B. SPRING.
